UNITED STATES PATENT OFFICE.

ADOLPH RICKENBACHER, OF LOS ANGELES, CALIFORNIA, ASSIGNOR OF ONE-HALF TO
GEORGE MATTHYSEN, OF INGLEWOOD, CALIFORNIA.

HINGE.

Application filed March 5, 1925. Serial No. 13,162.

This invention has to do with a hinge and it is an object of the invention to provide a simple, effective and inexpensive hinge operable to yieldingly resist movement from 5 one or more positions.

My present invention is applicable generally to hinges, it being particularly applicable to the ordinary types of hinge construction, for instance, to ordinary strap hinges. 10 I have throughout this disclosure chosen to set forth two typical forms of the invention as applied to a simple and typical form of hinge, it being understood that such reference is intended merely to facilitate a clear understanding of the nature of 15 the invention.

It is an object of my present invention to provide a hinge of the character described, which is extremely simple, inexpensive and compact in construction.

A further object of my invention is to provide a hinge of the character described embodying very few, simple and inexpensive parts.

The various objects and features of my invention will be best and more fully understood from the following detailed description of typical forms of the invention throughout which description reference is had to the accompanying drawings in which—

Fig. 1 is a front elevation of a simple form of hinge embodying my present invention.

Fig. 2 is a detailed plan section taken as indicated by line 2—2 on Fig. 1.

Fig. 3 is a detailed plan section taken as indicated by line 3—3 on Fig. 1.

Fig. 4 is a fragmentary view showing a portion of the parts illustrated in Fig. 1 in another position.

Fig. 5 is a view similar to Fig. 1 illustrating another form of my invention.

Fig. 6 is a detailed plan section taken as indicated by line 6—6 on Fig. 5.

Fig. 7 is a detailed plan section taken as indicated by line 7—7 on Fig. 5, and

Fig. 8 is a fragmentary view of a portion of the view shown in Fig. 5 showing the parts in another operative position.

In Figs. 1, 2, 3 and 4 of the drawings I illustrate a hinge comprising two sections 10 and 11 pivotally connected by a pivot pin 12. The hinge being of simple construction the sections comprise flat flange like bodies 13

adapted to be attached to the parts to be connected by the hinge. The hinge section 10 is provided at the inner end of the body 13 with two spaced bearing parts 14 while the section 11 is provided at the inner 60 end of its body 13 with a bearing part 15. The bearing parts of the two sections mesh together, that is the bearing part 15 fits between the bearing parts 14, and the pivot pin 12 extends through the bearing parts to 65 pivotally connect the sections. The pivot pin may be retained in position in the bearing parts in any suitable manner, for instance, it may be provided at its ends with heads 16 which engage the outer ends 70 of the bearing parts 14 so that the pin is held against longitudinal movement relative to the bearing parts 14. In the particular form of construction shown in the drawings the hinge sections are formed of sheet metal, 75 the bodies 13 being in the form of flat straps or plates and the bearing parts 14 and 15 being formed by bending or looping tabs or projections provided at the inner ends of the bodies. This is the usual construction 80 employed in simple hinges.

My present invention provides means in connection with the hinge sections 10 and 11 whereby they are yieldingly held against operation or relative movement when in certain positions. In the form of the invention under consideration the bearing part 15 of the hinge section 11 fits between the bearing parts 14 of the hinge section 10 with substantial clearance so that the hinge sections 90 are movable relative to each other a certain amount in a direction parallel to the pivot pin. For purpose of example we will consider that the hinge section 11 is to be mounted on a stationary part such as a case- 95 ment and that the hinge section 10 is to be applied to a movable part such as a door, or the like. This being the case the bearing part 15 of the hinge section 11 will in operation be stationary while the bearings 14 100 of the hinge section 10 will be movable both rotatably and longitudinally. My invention provides interengaging means at the adjoining ends of two of the relatively movable bearing parts, for instance, it provides a 105 projection 20 on the inner end of one of the bearing parts 14 and a depression or socket 21 in the adjoining end of the bearing part 15. In the particular case under consideration the projection 20 is provided 110

on the inner or lower end of the uppermost bearing part 14 while the socket 21 is in the upper end of the bearing part 15. During normal operation of the hinge the projection 20 engages or bears against the flat upper end of the bearing part 15 thus maintaining the hinge section 10 in an up position with relation to the hinge section 11. This relating or positioning of the parts is illustrated in Fig. 1 of the drawings. Upon the hinge being operated to a predetermined position, for instance, to a certain open position, the projection 20 drops into the socket 21 thus allowing the hinge section 10 to drop or lower relative to the hinge section 11. This dropping or lowering of the hinge section 10 is accomplished through the action of gravity. The weight of the hinge section 10, or of the door or other part carried thereby, will maintain the projection 20 in the socket so that the hinge sections are yieldingly held in this particular relative position. The projection is shown in the socket in Fig. 4 of the drawings. When it is desired to move the hinge section 10, or in other words, the door or device connected to the hinge section 10, sufficient turning strain may be applied to the hinge section 10 to cause the projection 20 to lift out of the socket and into position where it engages the upper part of bearing 15. In practice the disengagement of the projection 20 from the socket 21 may be aided by lifting the hinge section 10 upwardly at the same time it is turned. Although I have shown only one socket 21 it will be obvious that a plurality of sockets may be provided in the upper end of the bearing 15 so that the hinge sections may be yieldingly held in a plurality of different positions.

In the form of invention illustrated in Figs. 5, 6, 7 and 8 of the drawings the hinge sections 10^a and 11^a may be substantially the same as those hereinabove described, for instance, each hinge section may include a body 13, one of the sections, for instance, the section 10 may include, two spaced bearing parts 14^a, the other section a single bearing part 15^a, which fits between the bearing parts 14^a. In this form of my invention the bearing part 15^a fits between the bearing parts 14^a with only working clearance so that the two hinge sections are not relatively movable in a direction longitudinal of the pivotal axis. In this form of the invention the sections are connected by a tubular pin 12^a. A rod 12^b is slidably carried in the tubular pin 12^a, and projects beyond the ends of the pin. The rod is provided at the one end with a projection 20^a adapted to cooperate with a depression or socket 21^a provided in the outer end of one of the bearing parts 14^a. In the particular case illustrated in the drawings the projection 20^a is provided at the inner side of a head 30 formed on the upper end of the rod. The rod is adapted to move vertically relative to the upper bearing parts and to rotate relative to the bearing parts 14^a but not relative to the bearing part 15^a. The rod may be held against rotation relative to the bearing part 15^a in various ways, for instance, the body on which the part 15^a is formed may have a projection in the form of a stop 32 to engage a flat part 33 at the lower end of the rod, so that the rod can slide longitudinally, but cannot rotate. This form of the invention includes means for normally holding or urging the rod 12^a down or in a direction to hold projection 20^a in pressure engagement with the upper bearing part 14^a or in the socket 21^a, as the case may be. This means may include a spring 40 in connection with the rod. In the drawings I have shown the spring 40 in the form of a helical spring carried on the lower end portion of the rod below the lower end of the lower bearing part 14^a. The spring 40 is arranged under compression between the lower bearing part 14^a and a nut 41 screw threaded on the lower end of the rod. By adjusting the nut on the lower end of the rod the spring can be adjusted.

During normal operation of the hinge the rod 12^b is in up position, the projection 20^a being in engagement with the flat upper end of the upper bearing part 14^a. Upon the hinge parts being moved to a predetermined position the projection 20^a drops into the socket 21^a the rod being urged downwardly by the action of the spring 40. The projection 20^a is shown in position in the socket 21^a in Fig. 8 of the drawings. The fitting of the projection 20^a into the socket 21^a causes the hinge sections to be yieldingly held against relative rotation or operation the amount of resistance offered being dependent upon the adjustment of the spring 40. When it is desired to move the hinge sections from the set position suitable pressure may be applied tending to rotate them relatively whereupon the projection 20^a will lift or ride out of the socket 21^a so that the projection engages the flat end of the bearing part 14^a and allows the hinge section to swing freely. The pivot pin 12^a takes the wear and strain coming between the sections and allows the rod 12^b to operate freely and without binding. In this case a plurality of sockets 21^a may be provided in the bearing part 14^a if it is desired that the hinge have a plurality of set positions.

Having described only a typical preferred form of my invention I do not wish to limit myself to the specific details set forth, but wish to reserve to myself any changes or variations that may appear to those skilled in the art or fall within the scope of the following claims.

Having described my invention, I claim:

1. A hinge including two sections, a bearing part on each section, a tubular pin extending through the bearing parts, a rod slidably carried in the pin, a socket in one of the bearing parts, a projection directly on the pin, means for preventing rotation of the pin relative to the other bearing part, and means urging the pin in a direction to cause the projection to engage the socket.
2. A hinge including two sections, a bearing part on each section, a tubular pin extending through the bearing parts, a rod slidably carried in the pin and having a flat part, a socket in one of the bearing parts, a projection on the rod at one end, means for preventing rotation of the rod relative to the other bearing part, said means including a part extending from the section having said other bearing part engaging the flat part on the rod, and means at the other end of the rod urging the rod in a direction to cause the projection to engage the socket.

In witness that I claim the foregoing I have hereunto subscribed my name this 23rd day of Feb., 1925.

ADOLPH RICKENBACHER.
